DESIGN FOR A COAT

Samuel Lipman, New York, N. Y.

Application June 25, 1936, Serial No. 63,469

Term of patent 3½ years

To all whom it may concern:

Be it known that I, Samuel Lipman, a citizen of the United States of America, residing in Manhattan, county of New York, and State of New York, have invented a new, original, and ornamental Design for a Coat, of which the following is a specification, reference being had to the accompanying drawing, forming part thereof, wherein,

The characteristic feature of my design resides in the collar member of the coat, which is multi-stitched and raised in the rear, and has side flaps appearing as simulated bows at its sides.

I claim:

The ornamental design for a coat, substantially as shown and described.

SAMUEL LIPMAN.
